OSCILLOGRAPH CIRCUIT TO AVOID
DISTORTION

Meyer Maron, Passaic, N. J., assignor to Allen B.
Du Mont Laboratories, Inc., Passaic, N. J., a
corporation of Delaware

Application September 21, 1946, Serial No. 698,487

8 Claims. (Cl. 315--24)

1

This invention relates to a polar coordinate cathode-ray tube oscilloscope. Heretofore objections have been encountered with oscilloscopes of this sort due to the fact that the pattern traced on the face or screen of the tubes was often distorted by defocusing of the beam or the pattern was subjected to trapezoidal distortion.

With the present invention a circuit is provided of such a character that the average potential of the four deflection plates of an oscilloscope is maintained at the potential of the second anode of the cathode-ray tube.

The invention may be understood from the description in connection with the accompanying drawing which is a diagram showing a cathode-ray tube and connections thereto.

In the drawing, reference character 1 indicates a cathode-ray tube that is provided with a heater 2, cathode 3, control grid 4, first anode 5, second anode 6, a pair of horizontal deflection plates 7, and a pair of vertical deflection plates 8.

A triode 10 has its plate connected to a source B of positive potential. The cathode 11 of this triode is connected to one end of a series of resistances 12, 13, 14 and 15, the other end of this series of resistances being connected to a large negative potential.

A lead 16 extends from the control grid of tube 10 to ends of resistances 17, 18, 19 and 20. The other ends of resistances 17 and 18 are connected to opposite plates 7 of the oscilloscope 1 and the resistances 19 and 20 are connected to opposite plates 8 respectively. The resistances 17 to 20 are each large enough to reduce the coupling of the plates 7 and 8 to a negligible amount. A lead 21 extends from the cathode of tube 10 to the second anode 6. A lead 22 extends from a sliding contact on potentiometer 13 to the first anode 5 for focussing the cathode-ray beam of tube 1. Lead 23 extends from a sliding contact on potentiometer 15 to the control grid 4 for intensity control and lead 24 extends from a point between resistances 14 and 15 to the cathode 3.

Leads, 31, 32, 33 and 34 are connected to the pairs of deflection plates 7 and 8 in the usual way when the device is to be used to cause the beam to trace a pattern on the luminescent face of the tube. These leads 31 through 34 are connected to the usual and well known beam deflection and positioning circuits identified in block diagram form by the numerals 35 and 36 in the drawing, to provide beam deflecting and centering potentials for the cathode ray tube.

The lead 16 and grid of tube 10 are kept at a

2

potential that is the average potential of the pairs of deflection plates 7 and 8 by being connected to said plates through resistors 17, 18, 19 and 20. The cathode of tube 10 and the second anode 6 are maintained at the same potential since they are directly connected by lead 21. The potential of lead 16 differs from that of lead 21 only to the extent of the operating grid bias of tube 10. Therefore the potential of lead 21 and second anode 6 is kept very close to that of the pairs of deflection plates 7 and 8.

It will be obvious that when the average potential of the two pairs of plates 7 and 8 is provided by the same signal, or when the same signal is modulating both pairs of plates similarly, the resistances 17-20 need to be connected to only one pair of plates, since the average potential of the other pair of plates is then the same as that of the first pair.

What is claimed is:

1. An oscilloscope comprising a cathode-ray tube, having pairs of deflection plates and a first and a second anode, and means comprising a vacuum tube and a resistor between each one of said plates and the grid of said vacuum tube to maintain said second anode substantially at the average potential of said plates, said means including a connection between the cathode of said vacuum tube and said second anode.
2. An oscilloscope comprising a cathode-ray tube having pairs of deflection plates and a first and a second anode, and means comprising a vacuum tube and a resistor between each one of said plates and the grid of said vacuum tube to maintain said second anode substantially at the average potential of said plates, said means comprising a vacuum tube to the control grid of which said plates are connected and to the cathode of which said second anode is connected.
3. An oscilloscope comprising a cathode-ray tube having pairs of deflection plates and a first and a second anode, and means comprising a vacuum tube and a resistor between each one of said plates and the grid of said vacuum tube to maintain said second anode substantially at the average potential of said plates, said means comprising a vacuum tube to the control grid of which said plates are connected through high resistances and to the cathode of which said second anode is connected.
4. An oscilloscope comprising a cathode-ray tube having pairs of deflection plates and an anode, and means comprising a vacuum tube and a resistor between each one of said plates and the grid of said vacuum tube to maintain

said second anode substantially at the average potential of said plates, said means comprising a vacuum tube to the control grid of which said plates are connected through high resistances sufficient to prevent objectionable coupling between said plates and to the cathode of which said second anode is connected.

5. An oscillograph comprising a cathode-ray tube having pairs of deflection plates and an anode, and means comprising a vacuum tube and a resistor between each one of said plates and the grid of said vacuum tube to maintain said second anode substantially at the average potential of said plates, said means comprising a vacuum tube to the control grid of which said plates are connected, said vacuum tube having a high resistance in its cathode circuit and to the cathode of which said second anode is connected.

6. An oscillograph comprising a cathode-ray tube having pairs of deflection plates and an anode, and means comprising a vacuum tube and a resistor between each one of said plates and the grid of said vacuum tube to maintain said second anode substantially at the average potential of said plates, said means comprising a vacuum tube to the control grid of which said plates are connected, said vacuum tube having a high resistance in its cathode circuit, said vacuum tube having its cathode connected to said anode.

7. An oscillograph comprising a cathode-ray tube having pairs of deflection plates and a first anode and a second anode, and means comprising a vacuum tube and a resistor between each one of said plates and the grid of said vacuum tube to

maintain said second anode substantially at the average potential of said plates, said means comprising a vacuum tube to the control grid of which said plates are connected, said vacuum tube having a high resistance in its cathode circuit, said second anode being connected to the cathode of said vacuum tube and said first anode in said cathode-ray tube connected to said high resistance.

10. An oscillograph comprising a cathode-ray tube having pairs of deflection plates and a first anode and a second anode, and means comprising a vacuum tube and a resistor between each one of said plates and the grid of said vacuum tube to maintain said second anode substantially at the average potential of said plates, said means comprising a vacuum tube to the control grid of which said plates are connected, said vacuum tube having a high resistance in its cathode circuit, said second anode being connected to the cathode of said vacuum tube and said first anode in said cathode-ray tube adjustably connected to said high resistance.
